United States Patent Office

Des. 204,987
Patented June 7, 1966

204,987

COMBINED INTERCOM HOUSING AND SUPPORT THEREFOR

Roland N. Iverson, Dallas, Tex., assignor to Wells Television, Inc., New York, N.Y., a corporation of New York

Filed May 24, 1965, Ser. No. 85,435

Term of patent 14 years

(Cl. D26—13)

FIGURE 1 is a perspective view of a combined intercom housing and support therefor showing my new design;

FIGURE 2 is an elevational view thereof from the rear side;

FIGURE 3 is an end elevational view thereof;

FIGURE 4 is a top plan view; and

FIGURE 5 is a bottom plan view.

I claim:

The ornamental design for a combined intercom housing and support therefor, substantially as shown.
